UNITED STATES PATENT OFFICE.

HERMAN F. C. SCHULTZ AND FRED W. SCHULTZ, OF YOUNGSTOWN, OHIO.

FASTENING DEVICE.

1,422,482.

Specification of Letters Patent. Patented July 11, 1922.

Application filed April 12, 1921. Serial No. 460,672.

To all whom it may concern:

Be it known that we, HERMAN F. C. SCHULTZ and FRED W. SCHULTZ, citizens of the United States, residing at Youngstown, 5 in the county of Mahoning and State of Ohio, have invented certain new and useful Improvements in Fastening Devices, of which the following is a specification.

This invention relates to fastening devices, the primary object being to produce 10 an efficient device for tying together the free ends of open metal rings designed to secure traction or non-skid members to rubber tires, whereby the same may be securely attached, and readily detached.

In the accompanying drawings, Figure 1 represents a side elevation of the wheel with our invention attached.

Figure 2 is a sectional view on an enlarged 20 scale on line 2—2, Figure 1.

Figure 3 is a view in perspective, showing one of the four quarter sections of which our device is preferably made.

Figures 4 and 5 are details, illustrating 25 the manner in which the different sections are locked together.

Figure 6 is an illustration of our holding ring formed in one piece, rather than in sections as it would preferably be made.

30 Similar reference characters designate corresponding parts of the device throughout the various figures of the drawings.

AA, Figure 2, represent oppositely disposed holding rings, which we preferably 35 form of four quarter sections, a^1 , a^2 , a^3 and a^4 , as illustrated and designated in Figure 1. It is obvious, however, that these rings 40 may be formed of one section only, as shown in Figure 6, or of such number of sections as may be desired.

To rings AA we secure a plurality of cross-sections or non-skid elements bb, which may, of course, be of any desired type, having shown in the drawings a rigid cross bar 45 in oval formation to conform to the cross-section of the tire, carrying non-skid lugs cc on its outer or traction surface.

One end of each of two of the quarter sections, a^1 and a^3 as shown in the drawings, 50 is provided with a flat portion d, in which are formed a series of notches ee. The opposite end of a^1 is provided with an eye or opening f, while the opposite end of a^3 carries the outstanding pin g.

One end of each of the other quarter sections, a^2 and a^4 as shown in the drawings, is provided with an inwardly turned loop or slot h. The opposite end of a^4 is provided with an eye or opening f, while the opposite end of a^2 is provided with the outstanding pin g. Loosely and slidably mounted upon a^2 and a^4 , adjacent the integral loop h, is the locking loop or link i.

In assembling our device and securing it to the wheel, the flattened end d of section a^1 65 is passed through the slot h on the adjacent end of section a^4 , and after seating the inner wall of the slot h in one of the notches e, the sliding link or loop i mounted upon a^4 is moved forward to engage the flat end 70 or portion of a^1 , thus binding these two ends of a^1 and a^4 securely together. For the purpose of retaining the holding link i in its locking position, the cotter pin j may be used.

In a similar manner, the diametrically oppositely disposed adjacent ends, a^2 and a^3 , are locked together in exactly the same manner, and further description is unnecessary.

The adjacent ends of sections a^1 and a^2 , 80 and of a^3 and a^4 respectively, are fastened together by engaging the pin g in the eye f, where they may be secured by the cotter pin k.

We claim:

1. In a device of the character described, a separable fastener, one element of which has a flattened portion provided with a series of notches, the other element carrying a loop bent at substantially right angles, 90 and a link slidably mounted upon said second element.

2. In a device of the character described, a separable fastener, one element of which has a flattened portion provided with a 95 series of notches, the other element carrying a loop bent at substantially right angles, the inner wall of which is adapted to engage said notches, and a link slidably mounted upon said second element.

In testimony whereof we hereunto affixed our signatures in the presence of two witnesses.

HERMAN F. C. SCHULTZ.
FRED W. SCHULTZ.

Witnesses:

ALICE McGINN,
TROY C. TRITT.
